UNITED STATES PATENT OFFICE.

ALBERT W. THOMPSON, OF MANCHESTER, NEW HAMPSHIRE.

HUMIDIFYING APPARATUS.

No. 869,945.

Specification of Letters Patent.

Patented Nov. 5, 1907.

Application filed August 13, 1907. Serial No. 388,328.

To all whom it may concern:

Be it known that I, ALBERT W. THOMPSON, a citizen of the United States, and resident of Manchester, county of Hillsboro, State of New Hampshire, have invented 5 an Improvement in Humidifying Apparatus, of which the following description, in connection with the accompanying drawing, is a specification, like letters on the drawing representing like parts.

This invention relates to apparatus for imparting 10 additional humidity or moisture to the air in factory or other buildings where it is often desirable to increase the natural humidity of the air. Numerous devices have been provided for such purpose, varying in complexity of structure, general efficiency, and ease of adjustment, and my present invention has for its objects 15 the production of highly efficient but very simple humidifying apparatus, readily and quickly adjustable, of relatively small cost for installation and maintenance, and which by a very slight change can be used equally 20 well with either air under pressure or steam according to the season of the year and the convenience of the user. The water is not under pressure and the amount used may be regulated at one point for the system in a room or group of rooms, or by means of suitable valves 25 controlling the individual nozzles or vaporizers, and in the latter case the initial adjustment of the nozzle members would not be disturbed. While I can regulate the quantity and fineness of the spray to meet 30 widely varying requirements, simplicity of construction and easy accessibility for adjustment or cleaning have been retained, together with low cost of production.

My improved apparatus is so constructed and arranged that there is no obstruction whatever of light, 35 and there is no necessity for providing more or less cumbersome drainage devices, as by means of my invention the water is so thoroughly broken up and vaporized that precipitation of moisture in drops is obviated and hence there is no drainage to be taken care of. The 40 water supply is maintained at a constant level by any usual or suitable means, and as the water is not under pressure there is no possibility of damage from overflow, or leaks at the vaporizers or nozzles. By regulating the pressure of the vaporizing fluid the amount of spray can 45 be governed for an entire system or it may be governed by individual adjustment of the several nozzles, as will appear hereinafter.

The structure of the nozzle involves certain novel 50 features, whereby the jet of fluid under pressure creates a vacuum which is utilized in lifting the water to be vaporized, the energy of the jet being devoted to the thorough pulverization of the particles of water. This is true whether air under pressure or steam be employed as the active medium, but in the case of steam 55 certain slight modifications in the nozzle are preferably

made, as will be pointed out, in order to secure the greatest efficiency.

The various novel features of my invention will be fully described in the subjoined specification and particularly pointed out in the following claims.

Figure 1 is a perspective view of a sufficient portion of an installation of humidifying apparatus embodying one form of my invention, showing the preferred relative arrangement of the supply pipes or conduits for the water and fluid under pressure, with the connections 60 therebetween and the vaporizers or nozzles; Fig. 2 is an enlarged side elevation of one of the vaporizers or nozzles, arranged for use with compressed air; Fig. 3 is a front elevation thereof; Fig. 4 is a vertical section on the line 4—4, Fig. 3, the general shape of the jet of vapor 70 being indicated by dotted lines; Fig. 5 is a side elevation illustrating the modified form of the water inlet member when the nozzle is to be used with steam as the active medium; Fig. 6 is a longitudinal sectional view of the complete nozzle or vaporizer adapted for use with 75 steam, the shape of the jet of vapor being indicated by dotted lines; Fig. 7 is a detail showing in section a shield preferably attached to the vaporizer when using steam, for a purpose to be described.

In the present embodiment of my invention I have 80 shown the nozzles mounted in such manner that the jets of vapor will be expelled in a substantially horizontal direction, as I find that highly satisfactory results are thereby attained in practice, but the nozzles may be set at angles if desired.

Referring to Fig. 1 the water is obtained from a main supply pipe or conduit W^X , provided at desired intervals with couplings w having upright nipples w' each nipple being equipped as herein shown, with a valve w^X of any suitable construction, a length of preferably 85 rubber or other flexible tubing w^a connecting each nipple with the water inlet member of one of the nozzles or vaporizers indicated in Fig. 1 at V. The normal water level in the nipples is indicated at $W L$, the tops of the nipples in practice being well above the 90 water level, and such level may be maintained in the system in any well known way, as by a tank and float valve, to regulate the inflow of water to the tank, from which leads the supply conduit or pipe W^X , the nipples being long enough to prevent the formation of air pockets in the supply conduit, and also 95 preventing any danger of overflow should the connection between the nipple and the adjacent-vaporizer become disconnected. As such means of regulation of the water level forms no part of my invention and 100 is in constant use in many structures it is not herein illustrated. The pipe or conduit F^X for the fluid under pressure, air or steam, as the case may be, may parallel the water supply pipe W^X , as shown in Fig. 1, and opposite the nipples is provided with couplings f , 110

each having a threaded boss f' to receive the threaded end of the nozzle or vaporizer, to be described.

In the present embodiment of my invention I have shown each nozzle or vaporizer as comprising a head 5 containing a vacuum chamber and an apertured outlet, with an inlet for the fluid under pressure entering the chamber tangentially, and a water inlet member detachably connected with the head and having a water outlet axially located within the vacuum chamber 10 opposite the outlet thereof.

Referring to Figs. 2, 3 and 4 the head 1 is shown as cylindrical and internally threaded at its rear end, at 2, Fig. 4, its other end being closed by a thin diaphragm 3, herein shown integral with the head, and 15 having a central outlet opening 4, the head having a circular vacuum chamber 6, Fig. 4, with which the outlet 4 is coaxial. The head is made as a casting and has extended from one side thereof an integral tubular support 7, threaded at its end, at 8, to screw into the 20 boss f' of the coupling f , Fig. 1, the bore 9 of the support at its inner end being contracted and entering the side wall of the chamber 6 at 10, substantially tangential thereto, the opening 10 forming the inlet for the active medium or fluid under pressure.

25 As will be seen by reference to Figs. 4 and 6 the head portion of the nozzle or vaporizer is the same whether air or steam be used as the active or vaporizing medium, and I will first describe the water inlet member when using compressed air as the vaporizing fluid.

30 having reference to Figs. 2 and 4.

A screw-threaded plug 11 having an enlarged and preferably milled nut 12 is screwed into the head 1 and closes its open end, the plug having a central, tubular nozzle or outlet 13 communicating by a passage 14, 35 in the plug and nut, Fig. 4, with a hollow stem 15 at the outer end of the nut, terminating in a ball-like enlargement 16, the outlet 13 being made conical, tapering at its tip, at 17, and having a small orifice. The outlet 13 extends axially into the vacuum chamber 40 6, with its tip 17 opposite the outlet 4, and by screwing the plug 11 in or out the tip is moved toward or away from said outlet. The flexible tube w^2 is forced over the end 16 of the plug stem 15, and thereby communication is established between the water supply 45 in the connected nipple w^1 and the vacuum chamber of the particular nozzle or vaporizer, as will be manifest, by or through the water inlet member or plug. When the vaporizing fluid under pressure is admitted into said chamber through the inlet 10 the current as 50 sues a circular path of movement at high velocity around the chamber wall, the centrifugal action creating a vacuum therein as the current issues in jet form from the outlet 4. This vacuum is utilized in lifting and drawing over the water from the nipple to the 55 chamber 6 whenever the valve w^3 is opened, the energy of the jet being utilized in thoroughly and completely pulverizing or breaking up and vaporizing the particles of water and widely distributing the same, the jet issuing from the outlet 4 carrying the 60 moisture as aqueous vapor.

It will be manifest that the action described is totally different from that which obtains in vaporizers of the injector type, wherein the jet of fluid under pressure creates a vacuum by entrainment of the water, imparting 65 to the particles thereof a high velocity in approximately

parallel lines but with incomplete separation and distribution. The jet of aqueous vapor discharged by my improved nozzle or vaporizer is so free from water particles that there is no condensation, even upon cold metal surfaces, and the hand may be held in the jet 70 without the deposition of moisture thereon.

The low temperature of the expanding air issuing from the nozzle, with relatively large evaporation, has the maximum tendency to maintain low atmospheric temperature. Inasmuch as each degree the temperature is lowered increases the relative humidity this is of great advantage, especially in warm weather.

The quantity of water taken up can be regulated by regulation of the fluid under pressure, for the whole system, or by individual regulation of either the valve w^3 80 or the plugs 11 of the vaporizers, moving such plugs in or out as may be necessary.

By reference to the dotted lines in Fig. 4 it will be seen that the issuing jet of vapor J is of substantially parabolic outline, differing in that respect from the jet J^2 , Fig. 6, when steam is used as the fluid under pressure, the latter jet being quite sharply conical, as shown.

When using steam as the vaporizing medium I slightly change the construction of the water inlet member, in order to prevent heating of the incoming water while in 90 the inlet member, and to this end I provide the latter with a dead-air chamber.

Referring to Figs. 5 and 6, the plug 20, threaded to screw into and close the threaded end 21 of the head 1, is made hollow and internally threaded at its outer end at 95

21, Fig. 6, its inner end being made conical at 20 $^{\circ}$ and having a central or axial outlet 22, an annular enlargement 23 of the plug having a hole 24 communicating with its interior. Back of the said enlargement the plug is preferably made polygonal at 25, so that it may be gripped by a wrench or other suitable tool when applying it to the head. The other part of the inlet member comprises a water discharge nozzle 26 herein shown as enlarged and threaded at 27 to screw into the threaded part 21 of the plug, and having an enlargement 28 outside of a polygonal portion 29, the bore of the nozzle continuing through said enlargement 28, as shown in Fig. 6. The tip of the inlet nozzle is tapered to fit tightly against the end wall of the tapered closed end 20 $^{\circ}$ of the plug 20, see Fig. 6, with the nozzle opening registering 110 with the outlet 22 of the plug, a dead-air space or chamber 30 being formed in the plug and communicating with the outer air by the hole 24. Such air chamber serves to keep the nozzle 26 from becoming heated by the steam as it whirls around in the vacuum chamber 6 115 of the head, as without the chamber the entering water tends to become vaporized in the nozzle 26, thereby breaking up the vacuum and preventing the flow of water to the nozzle. The tip of the plug is set substantially as shown in Fig. 6, protruding slightly through the outlet 4, and the water tube w^2 is forced over the enlargement 28.

In operation the centrifugal action of the steam in creating the vacuum is the same as when air is employed, and the water is broken up and vaporized by the energy of the whirling fluid, assisted by the heat of the steam, but the latent heat absorbed by the vaporized water, and the re-evaporated condensation, reduces the temperature of the dry steam in the jet below the surrounding atmosphere, so that the effect of the jet as a whole is 125 130

cooling. The structure shown in Fig. 6 may be used for either steam or air equally well. The utilization of the energy of the fluid to break up and vaporize the water particles pertains whether the vaporizing fluid be compressed air or steam, and results in a very high mechanical efficiency for the nozzle.

When using steam any moisture contained therein is re-evaporated, which, with the heat absorbed by the vaporization of the water supplied to the nozzle, takes up the heat of the steam and cools rather than warms the surrounding atmosphere.

There is no drainage from condensation except at starting, and this slight amount can be collected in a suitable metallic shield, as shown at 40, Fig. 7, mounted on a collar 41 adapted to fit around the head of the nozzle, the opening in the shield being large enough to clear the jet of vapor and being incurved, as shown, to retain any condensate. A return-pipe 43 conveys the condensate to the water supply system without requiring any special piping.

It will be understood that the vaporizing nozzle will be introduced at such intervals as may be necessary to effect the desired results, but the vaporization of the water is so complete and the vapor jet discharged from each nozzle is of such ample proportions that a much smaller number of nozzles embodying my invention will be required for a room of given dimensions than would be necessary with less efficient forms of nozzles.

By reference to Fig. 1, it will be seen that anyone or more of the vaporizers V may be cut out by means of the valve u^X , and when so cut out, the operation of the other vaporizers is not interfered with in any way. When using air under pressure, the escape thereof at the cut out vaporizer would not be material, and if necessary or desirable each of the bosses f' could be provided with a shut-off valve.

When using steam as the vaporizing fluid, such valves would probably be advisable or the closure 20 could be screwed into the head 1, Fig. 6, far enough to bring its conical tip 20^X into position to close the outlet 4 of the vacuum chamber.

Having fully described my invention, what I claim as new and desire to secure by Letters Patent is:—

1. In humidifying apparatus, a head having a circular chamber provided with a tangential inlet for the admission of fluid under pressure, and an axial outlet at one end of the chamber, a water inlet member detachably connected with the head and closing the other end of the chamber, said member having a discharge nozzle extended into the chamber and terminating opposite and adjacent its outlet, and a tubular support integral with the head and communicating with the inlet of the chamber.

2. In humidifying apparatus, a head having a circular chamber provided at one end with an outlet, a tubular support for the head adapted to be connected with a supply of fluid under pressure and opening into the chamber tangentially thereto, combined with a water inlet member adjustably mounted on the head and closing the end of the chamber opposite its outlet end, a discharge nozzle on said member extending axially into the chamber, and means to connect the inlet member with a water supply.

3. In humidifying apparatus, a head having a circular chamber provided with a tangential inlet and internally threaded at one end, the opposite, closed end having a central outlet opening, means to connect the inlet with fluid under pressure, a centrally apertured plug adapted to be screwed into the threaded end of the head and closing the chamber, a discharge nozzle extending from said plug axially into the chamber, and an extension on the outer end of the plug adapted to be connected with a water supply.

4. In humidifying apparatus, a head having a circular chamber provided with a tangential inlet for the admission of fluid under pressure, and an axial outlet at one end of the chamber, a water inlet member closing the other end of the chamber and provided with a discharge nozzle extended axially into the chamber, means to adjust the nozzle toward and from the outlet of the chamber, said inlet member being adapted for connection to a water supply, and a tubular support for the head, communicating with the inlet of the chamber.

5. In humidifying apparatus, a circular closed chamber having an outlet at one end and an inlet for admission tangentially thereto of fluid under pressure, and means to introduce water into the chamber axially thereof, the centrifugal force of the fluid under pressure creating a vacuum in the chamber to draw water thereinto while the energy of said fluid is utilized in vaporizing the water.

6. In humidifying apparatus, a closed chamber having an outlet at one end, means to introduce a vaporizing fluid under pressure to said chamber and to effect rotary motion thereof in the chamber to create a vacuum, and means to introduce a liquid at atmospheric pressure into the chamber opposite its outlet, the energy of the fluid under pressure vaporizing the liquid and discharging the same as a vapor jet from the outlet of the chamber.

7. In humidifying apparatus, a head having a closed circular chamber provided with a central outlet at one end, a tubular support integral with the head and communicating tangentially with the chamber, means to connect the support with a supply of fluid under pressure, a water inlet member mounted on the head and having a discharge nozzle extended into and coaxial with the chamber, and means on the exterior of said inlet member to connect the same with a water supply.

8. In humidifying apparatus, a head having a circular chamber provided with a tangential inlet for the admission of fluid under pressure, and an axial outlet at one end of the chamber, a water inlet member mounted on the head and having a discharge nozzle extended into and coaxial with said chamber, and an open chamber surrounding the nozzle and separated from the chamber in the head.

9. In humidifying apparatus, a head having a circular chamber provided with a tangential inlet for the admission of fluid under pressure, and an axial outlet at one end of the chamber, combined with a two-part water inlet member comprising a tubular closure for one end of the chamber in the head, extended into said chamber and having a conical, apertured tip, and an inner member secured to the closure and provided with a water discharge nozzle extending into and against the inner wall of the apertured tip of the closure, the nozzle opening registering with the aperture, to form an air chamber between the closure and the nozzle, and external means on the latter to connect the same with a water supply, said air chamber being in continuous communication with the external air.

10. In humidifying apparatus, a supply pipe for fluid under pressure, a series of vaporizers mounted thereon, each having a closed chamber provided with an outlet, and with a tangential inlet communicating with the supply pipe, and a water inlet member communicating axially with the chamber, a water supply pipe having a series of upright nipples, a controlling valve for each nipple, and a connection between each nipple and the water inlet member of an adjacent vaporizer, the water in the supply pipe being under normal atmospheric pressure.

11. In humidifying apparatus, a series of vaporizers each having a closed chamber provided with an outlet and with a tangential inlet, and a water inlet member communicating axially with the chamber, means to supply fluid under pressure to the said tangential inlets, a water supply pipe having a series of upright nipples in which water is maintained at a constant level, and a connection between each nipple and the water inlet member of an adjacent vaporizer, the water in the supply pipe being under normal atmospheric pressure.

12. In humidifying apparatus, a series of vaporizers each having a closed chamber provided with an outlet and with a tangential inlet, and a water inlet member communicating axially with the chamber, means to supply

fluid under pressure to the said tangential inlets, and means to supply water under normal atmospheric pressure to the water inlet members of the several vaporizers.

13. In humidifying apparatus, a series of vaporizers each having a closed chamber provided with an outlet and with a tangential inlet, and a water inlet member communicating axially with the chamber, means to supply fluid under pressure to the said tangential inlets, an upright nipple connected with the water inlet member of each vaporizer, and means to supply water at normal atmospheric pressure to the several nipples, the water being maintained at a constant level in the nipples.

14. In a humidifying apparatus, a series of vaporizers, each having a closed chamber provided with an outlet and

with a tangential inlet, and means to supply fluid under pressure to said inlet, and with a water inlet member communicating axially with the chamber from below, and a water supply pipe communicating with the said water inlets, the water in the supply pipe being maintained at such pressure that the normal level of the water therein is below the level of the discharge orifices of the vaporizers when not in operation.

In testimony whereof, I have signed my name to this specification, in the presence of two subscribing witnesses.

ALBERT W. THOMPSON.
